UNITED STATES PATENT OFFICE.

THOMAS RICHARDS, OF JERSEY CITY, NEW JERSEY.

DESIGN FOR A PEN AND PENCIL CASE.

SPECIFICATION forming part of Design No. 18,410, dated June 26, 1888.

Application filed March 27, 1888. Serial No. 208,678. Term of patent 7 years.

To all whom it may concern:

Be it known that I, THOMAS RICHARDS, a citizen of the United States, residing at Jersey City, Hudson county, New Jersey, have invented a certain new and useful Design for Pen and Pencil Cases, fully described and represented in the following specification and the accompanying drawings, forming a part of the same.

10 The design relates only to the exterior of the holder; and it consists in a series of alternate flutes and longitudinal surfaces, the whole forming an approximately round body. The intermediate cylindrical surfaces are as wide as or wider than the flutes, so that the cylindrical surfaces may form a positive contrast to the concave surfaces of the flutes.

15 In the annexed drawings, Figure 1 is an end view of a pencil-case embodying my design, and Fig. 2 is a side view of the same. The proportions are somewhat enlarged in the drawings to show the form distinctly.

b are the flutes, and *C* are the longitudinal cylindrical surfaces intermediate to the flutes. The fluted surfaces may be left plain, as shown in the drawings, or engraved; but such matter is immaterial to my design.

The design is adapted for the cases of pens, pencils, tooth-picks, glove buttoners, or other holders; and

What I claim herein is—

The design for the exterior of a holder, consisting of alternate flutes and longitudinal cylindrical surfaces, substantially as herein shown and described.

In testimony whereof I have hereunto set my hand in the presence of two subscribing witnesses.

THOMAS RICHARDS.
